GAS MIXER

Filed Oct. 22 1925

UNITED STATES PATENT OFFICE.

FRANK W. GAULT, JR., OF LOUISVILLE, KENTUCKY, ASSIGNOR OF ONE-HALF TO
H. J. GREIVE, OF LOUISVILLE, KENTUCKY.

GAS MIXER.

Application filed October 22, 1925. Serial No. 64,182.

1 This invention relates to improvements in mixing chambers for furnaces, heat engines and like structures.

2 This invention consists of a mixing chamber 5 provided with a perforate diaphragm and having the gas and compressed air delivered to the mixing chamber at one side of the diaphragm whereby the compressed air will draw and carry the gas therewith 10 through the opening in the diaphragm and deliver it to the burner and burner nozzle connected to the mixing chamber on the opposite side of the diaphragm.

3 The invention consists of certain novel 15 features of construction and combination of parts which will be hereinafter described and pointed out in the claims.

4 In the accompanying drawings:

5 Figure 1 is a view in side elevation of the 20 invention;

6 Figure 2 is a view in vertical section;

7 Figure 3 is a top plan view in detail of the diaphragm shown in Figure 2;

8 Figure 4 is a detail view in top plan of a 25 modified form of diaphragm; and

9 Figure 5 is a section on line 5-5 of Figure 4.

10 The mixing chamber consists of two sections, a lower section 10 and an upper section 11, the upper section carrying a loosely 30 mounted ring 12 having internal screw-threads for engaging screw-threads 13 on the exterior portion of the lower section 10 for connecting the two sections together. Inter- 35 posed between the two sections is a metallic diaphragm 14. This diaphragm is provided with an opening 15 through the center thereof and the walls of the edge of the opening are bent downwardly into the lower section 40 10 and provided with radial slots or slits 16 radiating from the opening 15, throughout the downwardly extending portion or lips 17.

11 The lower section 10 is provided with a 45 central screw-threaded opening 18 in which is received a compressed air nozzle 19, which is provided with external screw-threads for engaging the internal screw-threads of the opening 18 so that the nozzle may be adjusted vertically with respect to the opening 50 15 of the diaphragm. A nut lock 20 is applied to the screw-threads of the nozzle 19 and adapted to engage lower edge of section 10 for holding the nozzle 19 in adjusted position. The nozzle 19 is provided at its lower

55 end with internal screw-threads 21 for engagement with the pipe 22 leading to the compressed air supply. The side walls of lower section 10 are provided with openings for the reception of pipes 23, 23 for the delivery of gas to the mixing chamber. 60

65 A nipple 24 is provided with external screw-threads 25 and has screw-threaded engagement with a tubular extension 26 formed on the upper section 11. This nipple is capable of being adjusted within the mixing 70 chamber of section 11 so that it may be moved from and toward the diaphragm and is held in adjusted position by means of a lock nut 27 mounted on the nipple and engaging the upper end of the tubular extension 26. Connected to the upper end of the nipple 24 by means of screw-threads 28 is a 75 burner nozzle 29. The burner nozzle in this instance being provided with a shell 30 which has screw threaded engagement therewith. 80 The burner nozzle 29 is shown connected directly to the nipple 24. However, it is my intention to also use this device in connection with manifolds, and in such instances the manifold is connected directly to the nipple 24, and the burner nozzle would then be connected to the manifold and a plurality of burners could be employed instead of a single burner. 85

90 The upper end of the upper section 11 is provided with a plurality of openings 31 for admitting air from the atmosphere to the mixing chamber and above the diaphragm 14. The amount of air that is admitted to the mixing chamber being controlled by a disk shaped valve 32. This valve is provided with a central opening 33 which surrounds the tubular extension 26 and a sufficient space is afforded between the extension 26 and the walls of the opening 33 to permit air to pass 95 therethrough to the openings 31 in section 11.

100 The disk valve 32 is provided with an annular flange 34 which has screw-threaded engagement with the exterior wall of the upper section 11 whereby the amount of air admitted to the mixing chamber may be regulated by adjusting the valve on the upper section 11. The valve is held in adjusted position by means of a set screw or nut 35.

105 In Figures 4 and 5 the diaphragm 14 is provided with a central opening 15 and is similar in construction to the diaphragm shown in Figures 2 and 3, but the down-

wardly extending truncated cone shaped portion or projection 36 is made solid and is not provided with slits or slots 16.

The diaphragm 14 is reversible so that the truncated portion may extend upwardly or downwardly in the mixing chamber and it controls the gas supply to the burners in the furnace by the size of the openings and the size of the slits or slots formed therein. The amount of gas delivered through the openings in the diaphragm is controlled by the size of the openings and only a proportional amount of gas will pass through a certain size orifice at a proportional pressure of compressed air.

In the operation of this device the gas is admitted to the mixing chamber through pipes 23 and compressed air through the nozzle 19, beneath the diaphragm 14. The gas and compressed air are brought together beneath the diaphragm, the compressed air drawing the gas therewith through the central opening of the diaphragm causing a thorough mixture of the gas with the compressed air and delivering it to the nipple 24 and burner nozzle 29. After the gas has been ignited at the nozzle the disk valve 32 will be adjusted upon the mixing chamber for governing the amount of atmospheric air admitted to the chamber and drawn thereinto by the blast of compressed air and gas passing through the chamber and into the nipple 24 for governing the intensity of the heat of the flame.

The adjustment of the nozzle 19 with respect to the diaphragm 14 governs the delivery or suction on the gas delivered through the diaphragm and the adjustment of the nipple 24 within the mixing chamber regulates the direct discharge of compressed air and gas into the nipple.

Claims:

1. In a gas mixer the combination of a mixing chamber, a perforate diaphragm therein, means for delivering gas and compressed air to the mixing chamber on one side of the diaphragm and discharging the gas and compressed air through the diaphragm, and a burner nozzle connected on the opposite side of the diaphragm to which the compressed air and gas are delivered and adjustable with respect to the opening in the diaphragm.

2. In a gas mixer the combination of a mixing chamber having a diaphragm there-

in said diaphragm provided with a central opening, means for delivering gas to the mixing chamber on one side of the diaphragm, and a compressed air nozzle adjustably connected to the mixing chamber and adjustable to and from the opening in the diaphragm for delivering compressed air to the mixing chamber and through the opening in the diaphragm for drawing the gas therethrough, and a burner nozzle connected to the mixing chamber on the opposite side of the diaphragm.

3. In a gas mixer the combination of a mixing chamber made in sections, a perforate diaphragm interposed between the two sections, means for connecting the two sections together and supporting the diaphragm, means for delivering compressed air and gas to the mixing chamber on one side of the diaphragm, a burner nozzle connected to the mixing chamber on the opposite side, said mixing chamber having openings therein for admitting air to the mixing chamber on the opposite side of the diaphragm, and a valve for controlling the admission of air through said openings.

4. In a gas mixer the combination of a mixing chamber having a reversible diaphragm therein provided with a central opening, said diaphragm having the central portion thereof extending laterally therefrom in the form of a truncated cone, means for delivering gas to the mixing chamber beneath the diaphragm, a compressed air nozzle for delivering compressed air to the mixing chamber beneath the diaphragm and adjustable with respect to the opening in the diaphragm, and a burner nozzle connected to the mixing chamber on the opposite side of the diaphragm.

5. In a gas mixer, the combination of a mixing chamber, a perforate diaphragm therein, means for delivering gas to the mixing chamber on one side of the diaphragm, a compressed air nozzle connected to the mixing chamber and adjustable to and from the opening in the diaphragm for governing the delivery of the gas through the diaphragm by the compressed air, and a burner nozzle connected to the mixing chamber on the opposite side of the diaphragm and adjustable to and from the diaphragm with respect to the opening in the diaphragm.
